EDWIN E. SLICK, OF WESTMONT BOROUGH, PENNSYLVANIA.

SPLICED REINFORCING-BAR.

1,109,258.

Specification of Letters Patent.

Patented Sept. 1, 1914.

Application filed October 6, 1913. Serial No. 793,500.

To all whom it may concern:

Be it known that I, EDWIN E. SLICK, a citizen of the United States, residing in the borough of Westmont, in the county of Cambria and State of Pennsylvania, have invented certain new and useful Improvements in Spliced Reinforcing-Bars; and I do hereby declare the following to be a full, clear, and exact description of the invention, such 10 as will enable others skilled in the art to which it appertains to make and use the same.

My invention relates to spliced reinforcing bars made of metal and adapted to be used 15 in metal concrete constructions or what is known as reinforced concrete construction, the bars being primarily adapted to resist stresses of tension.

My invention relates particularly to the 20 splice and joining of the overlapping ends of concrete reinforcing bars, which bars are provided with alternating projections and depressions adapted to fit into or interlock with each other. When the bars are placed 25 in position with comparatively short lengths overlapping, the projections of one bar fit into the depressions of the adjacent bar, and I secure the bars firmly together by means of a clamp formed of one piece of metal which 30 surrounds both bars neatly with a space at one end between the said clamp and the adjacent bar adapted to receive a metal wedge. This metal wedge is then driven firmly between the outer surfaces of one of the bars 35 and the adjacent interior surface of the clamp in such a way as to lock the two bars firmly together. By reason of the interlocking of the bars, the form and dimensions of the surrounding clamp and the action of the 40 wedge, the projections of one bar are forcibly pressed into the depressions of the other bar in such a way that the stresses of tension in said bars, when in service, will be resisted by the interlocks which are firmly held together by the clamp and wedge, and in addition the large amount of friction induced by the pressure of the wedge and the stresses of tension adds materially to the strength of the joint. In this way I am enabled to provide 45 a very simple form of splice for bars of the character described, so that the spliced ends will be of strength greater than that of the body of either bar, which is a desideratum in constructions of this character.

Ordinarily concrete reinforcing bars are 50 overlapped for splicing to an amount equal

to about forty diameters of the bar, and even this is insufficient to develop the strength of the bars, whereas by means of my splice, an overlap of eight or ten times the diameter of 55 the bar suffices to make the splice fully equal to, or of greater strength than, the bar. This splice may be applied to shorter bars in locations, where desired, but is particularly useful in cases where bars are needed of 60 lengths longer than those generally available. Concrete reinforcing bars are usually furnished in comparatively short lengths, and extreme lengths which are known as carload lengths, namely:—from thirty to 65 forty feet, and neither of these are adapted for constructions requiring longer lengths. This difficulty, however, is obviated by means of my spliced construction whereby 70 bars may be joined together to furnish any 75 lengths desired, and the joints in the same will be of strength greater than that of the body of the bar.

My construction is particularly adapted to bars having a central body portion and a 80 plurality of flanges projecting beyond the body portion, which flanges are curved or corrugated in the direction of their projections, the opposite edges of each pair of corrugated flanges being parallel to each other, 85 whereby the projections on each bar will neatly fit the depressions of a companion bar of the same kind. This form of concrete reinforcing bar is covered by my Patent No. 882,273, granted March 17th, 1908, and illustrated herein. My spliced construction, 90 however, is adapted to other forms of reinforcing bars and particularly to those which have alternating projections and depressions on their surfaces adapted to contact or interlock with corresponding depressions or projections on the companion bar of similar outline.

Having thus given this general description of my invention, I will now, in order to 100 make the same more clear, refer to the one sheet of drawings accompanying and forming part of this specification and in which like figures refer to like parts.

Figure 1 is a side elevation of a pair of 105 overlapping reinforcing bars spliced according to my invention, each of said bars having alternating projections and depressions adapted to fit and interlock; the depressions on one side of each of said bars are 110 opposite correspondingly shaped projections on the same side of the said bars; while

on the other side of each of said bars the 5 projections are opposite the depressions of the other side and the depressions are correspondingly opposite the projections of the other side. The view of one side of each of said bars, therefore, presents an undulating or waved appearance, the exterior lines of which are parallel to each other, while the other side presents a similar appearance, 10 with the exception that the locations of the projections and depressions are staggered with respect to the side first mentioned. Fig. 2 is a cross sectional elevation taken on the line II—II of Fig. 1. Fig. 3 is a 15 view similar to Fig. 2 with the exception that the wedge is of slightly different form. Fig. 4 is a view similar to Figs. 2 and 3 with the exception that the wedge has a different form. Fig. 5 is a side elevation 20 of a pair of overlapping reinforcing bars spliced according to my invention, the clamp being shown in central vertical section for the sake of clearness of illustration. It will be noted that the reinforcing 25 bars shown in Fig. 5 are slightly different from those shown in Fig. 1, in that the projections and depressions on the two sides of each bar are directly opposite each other, instead of being staggered. Fig. 6 is a 30 transverse vertical section on the line VI—VI of Fig. 5.

Referring now to the characters of reference on the drawings: 1—1 indicate reinforcing bars, each provided with alternating 35 projections and depressions adapted to fit together and interlock when one is superimposed upon the other as shown.

2—2 are projections; 3—3 are the depressions. These projections and depressions 40 are preferably formed, as shown in side elevation in Figs. 1 and 5, as continuous curves giving a sinuous or wave-like appearance to the bar, the outline of the projections being similar to that of the depressions, so that the projections will fit into the 45 depressions of a companion bar and the spacing of the said projections and depressions is substantially the same so that the bars will interlock as shown. The projections and depressions, however, may be made in other forms than shown, and may be bounded by straight lines, or a combination of straight lines and curves, as will be readily understood by one skilled in this art.

55 The projections 2 are disposed on the outer edges of the bar, thereby forming a groove therein indicated as 4.

5 indicates generally a clamp which is formed integrally of metal, shown in this 60 case as of rectangular outline. I prefer to make this clamp from a bar of flat iron or steel, cut to the length desired, with a hole formed in the center thereof by punching, either cold or hot, as may be desired. This, 65 therefore, forms a clamp of integral metal

provided with side portions 6—6 which are adapted to withstand the tensional and bending stresses of the clamp when in use, and end portions 7—7, which in connection with the sides 6—6 are adapted to withstand the shearing stresses and the slight amount of bending produced by the pressure of the wedge and the stresses due to the tension of the bars in use.

The lower end surface of the clamp 5 is 75 indicated as 8, which surface contacts with the external surface of the bar adjacent thereto, while the opposing interior end surface of the clamp is indicated as 9 which is adapted to contact with the adjoining surface of the wedge which is driven against it. 80

As shown in Figs. 1 and 2, 10 represents a wedge, the width of which is substantially equal to that of the bars 1—1 and is adapted to be inserted in the opening provided therefor between one of the said bars and the adjacent interior end surface 9 of the clamp 5. These wedges are preferably formed of hard metal and with comparatively slight taper so that the frictional resistance between the wedge, the clamp and the bar is sufficient to hold the same securely together when the wedge is forcibly driven into position.

As shown in Fig. 3, the wedge is formed 95 with the portion 11 of substantially rectangular cross section and with an integral lower portion 13 which is adapted to fit into and contact with the surface of the groove 4 in the bar 1, in addition to which, 100 the wedge has lower side surfaces 12—12 which are adapted to contact with the outer portions of the projecting surfaces 2—2 of the bars.

As shown in Fig. 4, the wedge is provided 105 with an upper portion 14 of substantially rectangular cross section with an integral taper portion 15 below the same adapted to contact only with that portion of the bar 1 which is formed by the sides of the groove 110 4 therein; the upper surface of the said wedge contacting with the upper interior end surface of the clamp 9 as before. The form of the wedge illustrated in Fig. 5 is the same as that illustrated in Fig. 3, having 115 an upper portion 11, the upper surface of which is adapted to contact with the interior end surface 9 of the clamp 5, and in addition is provided with a downwardly extending integral projection or tongue 13 120 adapted to fit in the groove 4 of the bar, while the lower surface 12 of the upper portion of said wedge also contacts with the outer surfaces of the projecting portions 2 of the bar.

125 Although I have shown and described my improvements in considerable detail, I do not wish to be limited to the exact and specific details shown and described, but may use such substitutions, modifications or 130

equivalents thereof, as are embraced within the scope of my invention, or as pointed out in the claims.

Having thus described my invention, what I claim and desire to secure by Letters Patent is:—

1. A pair of metal reinforcing bars, at least one of two opposite sides of each being provided with a plurality of sinuous projections and depressions fitted together and adapted to prevent relative longitudinal movement of said bars, an integral metal clamp surrounding said bars, adapted to contact with the other sides of said bars and one of the first mentioned sides of one of said bars so as to prevent the relative lateral displacement of said bars, thereby serving to hold the interlocking projections and depressions of the two bars in close engagement, and a wedge cooperating with said clamp and bars adapted to hold them firmly together.
2. A pair of rolled metal reinforcing bars, each of which is of substantially equal cross section throughout, two opposite sides of each of which are rolled substantially parallel, at least one of the other sides of each being provided with two rows of projections and depressions of curved outline rolled adjacent to the corners thereof forming sinuous surfaces adapted to fit together and interlock against longitudinal movement, a groove between said rows of projections, an integral metal clamp surrounding said bars adapted to contact with the parallel sides thereof and the outer surfaces of one of the

sinuous sides of one of said bars and thereby hold them in relative interlocking relation, a wedge inserted between one of said bars and the clamp, said wedge being provided with a flat surface on one side adapted to contact with the interior end surface of said clamp, the opposite side of said wedge having flat surfaces near the edges and a projecting rib between the same adapted to fit into and contact with the surface of the groove in said bars.

3. A pair of concrete reinforcing bars, each having a central body portion and a plurality of flanges projecting from two opposite sides beyond the body portion, at least two of said flanges being corrugated in the direction of their projection and the edges of the corrugated flanges being parallel; the ends of said bars overlapping and interlocking longitudinally by means of the corrugated flanges aforesaid, a clamp comprising an integral perforated piece of metal adapted to surround and to contact with the other sides of said bars so as to prevent the relative lateral displacement of said bars, thereby serving to hold the interlocking projections and depressions of the two bars in close engagement, and a wedge inserted between said clamp and the surfaces of one of the said bars.

In testimony whereof I hereto affix my signature in the presence of two witnesses.

EDWIN E. SLICK.
